COMMERCIAL BUILDING

George M. Wright, Jr., 4149 Druid Lane,
Dallas, Tex. 75205

Filed May 22, 1968, Ser. No. 12,044

Term of patent 14 years

Int. Cl. D25—04

U.S. Cl. D13—1

FIG. 1

FIG. 2

FIG. 1 is a front perspective view of a commercial building showing my new design;

FIG. 2 is a back perspective view of a commercial building showing my new design; and

FIG. 3 is an end elevation view of a commercial building showing my new design.

The right end of a commercial building showing my new design is like the left end elevation view shown in FIG. 3.

I claim:

The ornamental design for a commercial building, as shown and described.
